FILLING VALVE

Erwin R. Gaerttner and Max L. Yeater, Schenectady, N. Y., assignors to General Electric Company, a corporation of New York

Application August 17, 1949, Serial No. 110,852

3 Claims. (Cl. 137—21)

1

This invention relates to apparatus for the detection of ionizing radiation and more particularly to means for introducing gases into cloud chamber devices.

Apparatus which has been widely utilized for detecting ionizing radiations is known as the "Wilson Cloud Chamber." Such apparatus comprises generally a partially transparent airtight envelope enclosing a chamber of variable volume into which an ionizable gas and a condensable vapor are introduced. When ionizing radiations pass through the envelope into the chamber enclosed thereby, molecules of the ionizable gas will be ionized. Thereafter, if the chamber volume is suddenly increased, the temperature in the chamber will decrease and droplets of condensation will be formed about the ions which serve as centers for such condensation. Thus, the passage of the ionizing radiations through the chamber will be marked by tracks of ions about which condensation has been formed. These tracks may then be illuminated by visible light projected through the transparent portion of the envelope and viewed or photographed to provide a permanent record of the phenomenon.

In such apparatus considerable difficulty has been experienced in providing suitable means for introducing gases into the expandable chamber through an aperture in the enclosing envelope. After the gases have been introduced and the apparatus is placed in operation to obtain tracks of ionizing radiation, it is of prime importance that the means utilized for introducing the gases be of such a design and have such a location that the operation of the apparatus is not deleteriously affected. The envelope enclosing the chamber is, as mentioned heretofore, usually constructed of transparent material and, therefore, the gas introducing means must be capable of sealing an aperture in material such as glass or plastic without interfering with the viewing or photographing of the ion tracks. In some instances, a magnetic field is oriented to traverse the chamber, and in such event, the gas introducing means must be designed to avoid distortion of this field. Moreover, irregular protuberances within the envelope enclosing the expandable chamber will cause turbulence of the gas when the chamber is expanded to form droplets about the ions created by the ionizing radiation and, consequently, means employed for closing the aperture in the envelope must not present such a protuberance within the envelope. Furthermore, in order for accurate results to be obtained, it is essential that all impurities such as

2

dust particles be absent from the chamber because such impurities will serve as condensation centers as well as ions. Therefore, such impurities must be removed from the chamber and not introduced during the process of filling the chamber with the necessary gases.

In accordance with the present invention, these difficulties have been overcome by providing a small valve adapted to seal an aperture in the transparent envelope of cloud chamber apparatus. In its normal position this valve is maintained in a sealing location by means of an adjusting screw positioned exteriorly of the envelope. When it is desired to fill the chamber with gases, detachable means forming an enclosure and adapted to be sealed to the exterior of the envelope about the adjusting screw may be employed to open the valve and admit gases into the chamber.

20 The features which it is desired to protect herein are pointed out with particularity in the appended claims. The invention itself, together with further objects and advantages thereof, may best be understood by reference to the following 15 description, taken in connection with the accompanying drawing in which Fig. 1 is a sectional view of simplified cloud chamber apparatus in which the invention may find suitable application; Fig. 2 is a partial section of the valve portion of the invention in its normal sealing position; and Fig. 3 is a sectional view illustrating the detachable means for admitting gases into the cloud chamber apparatus.

25 Referring particularly to Fig. 1 there is shown a simplified cloud chamber apparatus in which an expandable chamber 1 is defined by a transparent glass or plastic cylinder 2, a cylindrical gasket 3, a circular transparent glass or plastic plate 4 and a flexible diaphragm 5. Cylindrical gasket 3 and flexible diaphragm 5 may consist of deformable material such as natural or synthetic rubber in order that chamber 1 may be maintained airtight.

30 For suitably supporting the above mentioned portions defining chamber 1 there is shown a cylindrical base member 6 having at its upper end an outwardly extending flange 7 against which the lower surface of flexible diaphragm 5 bears. Bolt members 8 and 9 attached to flange 35 7 serve to force clamping member 10, which may be circularly symmetrical, against the upper surface of plate 4, thereby assuring the proper sealing of chamber 1.

35 To provide a means of flexing diaphragm 5 for altering the volume of chamber 1, there is shown

a piston 12 having a shaft member 13 and a head member 14, the upper surface of which may be positioned against the lower surface of diaphragm 5. As indicated by the dotted lines, piston 12 may be moved upward thereby reducing the volume of chamber 1. In this latter position gases introduced into the chamber 1, in a manner to be hereinafter described, will be in a saturated state, but if piston 12 is moved suddenly downward into the position shown by the heavy lines, the volume of chamber 1 will be increased and droplets will be formed about condensation centers which are present in the chamber at the time. In order to facilitate the movement of piston 12, enclosure 15, defined in part by a flexible bellows 16 sealed to shaft member 13 and a flange 17, may be partially evacuated.

As mentioned heretofore, in order for the cloud chamber apparatus to be operated to obtain ion tracks, ionizable gases and condensable vapors must be introduced into chamber 1. However, after the gases have been introduced, and the apparatus placed in operation, the chamber 1 must be maintained relatively airtight in order to secure the proper pressure variations within chamber 1. To provide suitable sealing means, there is shown in Fig. 2 a valve 18 which in its normal position is adapted to seal an aperture 19 in glass plate 4 shown in Fig. 1. The valve comprises a threaded stem 20, inserted through aperture 19, and a head 21 attached to stem 20 and positioned within chamber 1. A gasket 22 of deformable material, such as natural or synthetic rubber, is positioned about stem 20 against the head 21. A cylindrical adjusting screw 23, having inner and outer threads, is placed with its inner threads engaging the threaded portion of stem 20 such that its lower end may bear against the outer surface of glass plate 4 and force head 20 and gasket 22 upward to seal aperture 19.

In order to provide means for operating valve 18 to admit gases to chamber 1, there is shown in Fig. 3 a threaded member 24 adapted to engage the outer threads of the adjusting screw 23 and to force a helical spring member 25 against a notched washer 26 which is supported by the outer surface of plate 4. A sleeve 27, supported by flange 28 and a fixed support 29, may be sealed to the exterior of plate 4 by means of a cylindrical gasket 30. A threaded thumb screw 31 may be employed to hold sleeve 27 against support 29 and in sealing position on the outer surface of plate 4.

Freely movable within the bore of sleeve 27 is a plunger 32 which has an upper boss 33 and a lower boss 34 serving to guide the movement within sleeve 27. Lower boss 34 may have apertures 35 and 36 in order to facilitate the passage of gases therethrough into or from chamber 1 in a manner to be more fully described hereinafter. Plunger 32 may be sealed within sleeve 27 by means of a flexible diaphragm 37 clamped between blocks 38 and 39 which are held together by screw members 40 and 41. Block 38 may be sealed to sleeve 27 in a conventional manner, such as by soldering or brazing at 38', and may also have a cylindrical groove 42 into which a matching cylindrical protuberance 43 upon block 39 fits to deform diaphragm 37 and thereby seal sleeve 27. Exterior longitudinal movement of plunger 32 within sleeve 27 may be obtained by the means of notched washer 44 positioned upon the outer surface of diaphragm 37 opposite the upper surface of plunger 32. Screw member 45, which engages a tapped hole in plate 46 secured to block

39, serves to hold washer 44 in place against the upper surface of diaphragm 37 by means of a tip 47 which turnably engages the notch in washer 44 to determine its position.

In Fig. 3 the means for operating valve 18 is shown in position to open valve 18 to admit gases into chamber 1. Assuming that valve 18 is in the position shown in Fig. 2 the means for operating the valve may be assembled in the following manner. Washer 26, spring 25 and threaded member 24 may be positioned about adjusting screw 23 such that spring 25 is placed in compression. Adjusting screw 23 may then be turned to move its lower end a suitable distance away from the exterior of plate 4. It will be apparent that head 21 and gasket 22 will still be retained against the inner surface of plate 4 because of the force of spring 25 and hence the sealing of aperture 19 is not affected.

After adjusting screw 23 has been moved away from the outer surface of plate 4, sleeve 27, along with plunger 32, may be positioned in sealing relation against outer surface of plate 4 about washer 26, spring 25, adjusting screw 23, stem 20, and threaded member 24. Thereupon, screw member 45 may be turned to force plunger 32 downward such that the lower surface of boss 34 will bear against the upper end of adjusting screw 23 and force stem 20 downward to open valve 18. It is to be presumed, however, that prior to the opening of valve 18, sleeve 27 will have been evacuated or filled with gases through a connection 48 which may be sealed to sleeve 27 in a convenient position along its bore. In the event that sleeve 27 is evacuated through connection 48, it should be observed that the force of spring 25 must be greater than the hydrostatic force on diaphragm 37 in order to prevent premature opening of valve 18.

While the invention has been described with particular reference to its advantageous application in cloud chamber apparatus, it will be apparent to those skilled in the art that the invention may find similarly advantageous application in other forms of apparatus. I aim in the appended claims, therefore, to cover such equivalent variations of use and structure which come within the true spirit and scope of the foregoing disclosure.

What we claim as new and desire to secure by Letters Patent of the United States is:

1. An envelope having an aperture through which gases may be admitted, a valve positioned normally to seal said aperture comprising a stem member extending through said aperture, a head member attached to the end of said stem within said envelope, a gasket fitting about said stem against said head member, a cylindrical adjusting screw having inner and outer threads, said inner threads engaging threads on the outer end of said stem whereby said gasket may be forced against the inner wall of said envelope, detachable means for operating said valve to admit gases into said envelope comprising a helical spring member positioned about said adjusting screw and having one end attached to a threaded member adapted to engage the outer threads of said adjusting screw whereby said spring member may be placed in compression and said adjusting screw may be moved outward with respect to said envelope without moving said stem, and means forming an enclosure adapted to be sealed to the exterior of said envelope about said spring member for forcing said adjusting screw inwardly

whereby said valve may be opened to admit gases into said envelope.

2. An envelope having an aperture through which gases may be admitted, a filling valve adapted in a normal position to seal said envelope and in an operating position to admit gases into the envelope comprising a stem extending through the aperture in said envelope, a head member attached to the end of said stem within said envelope, a gasket of deformable material fitting about said stem against said head member, a cylindrical adjusting screw having inner and outer threads, said inner threads engaging threads on the outer end of said stem whereby said gasket may be positioned against the inner wall of said envelope to seal the aperture in a normal position, detachable means for operating said valve to admit gases into said envelope comprising a helical spring member positioned about said adjusting screw, a threaded member engaging the outer threads of said adjusting screw and bearing against said spring member whereby said spring member may be placed in compression and said adjusting screw may be moved outward with respect to said envelope without moving said stem, and means forming an enclosure sealed to the exterior of said envelope about said spring member for forcing said adjusting screw inwardly whereby said valve may be opened to admit gases into said envelope.

3. In apparatus for the detection of ionizing radiation having an envelope of variable volume in which gases may be expanded to form condensation droplets about ions created by the pas-

sage of radiation through the envelope, a filling valve adapted in a normal position to seal the envelope and in an operating position to admit gases into the envelope comprising a stem fitting loosely through an aperture within a wall of the envelope, a head member attached to the end of said stem within the envelope, a gasket of deformable material fitting about said stem against said head member, a cylindrical adjusting screw having inner and outer threads, said inner threads engaging threads on the outer end of said stem whereby said gasket may be positioned against the inner wall of the envelope to seal the aperture, detachable means for operating said valve to admit gases into the envelope comprising a helical spring member positioned about said adjusting screw, a threaded member engaging the outer threads of said adjusting screw and bearing against said spring member whereby said spring member may be placed in compression and said adjusting screw may be moved outward with respect to the envelope without moving said stem, a sleeve about said spring member adapted to be sealed to the wall of the envelope, and a plunger sealed within said sleeve, said plunger being externally movable to force said adjusting screw, said stem, said head and said gasket inwardly against the force of said spring member whereby said valve may be opened to admit gases introduced into said sleeve into the envelope.
